[57] CLAIM

The ornamental design for a van top, substantially as
shown.

DESCRIPTION

FIG. 1 is a top, front and left side perspective view of a
van top showing my new design, it being understood
that the broken lines are for illustrative purposes only.
FIG. 2 is a rear elevational view thereof to an enlarged
scale;

FIG. 3 is a right side elevational view thereof to an
enlarged scale;

FIG. 4 is a top plan view thereof to an enlarged scale;
and

FIG. 5 is a bottom plan view thereof to an enlarged
scale.
